United States Patent Office.

WILLIAM H. HOUSTON, OF NEW YORK, N. Y.

Letters Patent No. 66,345, dated July 2, 1867.

IMPROVED BOAT-DETACHING APPARATUS.

The Schedule referred to in these Letters Patent and making part of the same.

TO ALL WHOM IT MAY CONCERN:

Be it known that I, WILLIAM H. HOUSTON, of New York, of the county of New York, in the State of New York, have invented certain new and useful improvements in Apparatus for Launching or Lowering Overboard Small Boats; and I do hereby declare that the following is a full and exact description thereof, reference being had to the accompanying drawings, making part of this application.

My invention relates to the mechanism or device employed for effecting the launching of life-boats from ships, and has for its objects to readily and with certainty effect the release of the boat as soon as it is fairly launched. And to these ends my invention consists in an automatic boat-eye or lock, so constructed and operating that when attached to the hook, by which the boat is suspended, it will automatically disengage or detach itself from said hook the moment the boat, or that part to which said lock is attached, rests fairly in the water.

To enable those skilled in the art to make and use my invention, I will proceed to describe more fully the construction and operation of my automatic or self-detaching boat-lock or eye, referring by letters to the accompanying drawings, in which—

Figure 1 is an elevation, illustrating a boat suspended ready to be launched, and having on it my invention.

Figure 2 is a similar view, showing the boat launched; and

Figure 3 is a sectional elevation of the automatic or self-detaching device.

Figure 4 is a similar section, showing another form of my invention.

In the several figures, A is a life-boat, and B is the arm or "davit," from which the boat is suspended, by means of the usual ropes C, passing through an eye in the outer end of said arm B, and provided with a suitable hook, d. To each end of the boat may be attached securely one of my automatic locks, as seen at F, figs. 1 and 2. This lock is composed of a metallic stock or stand portion, as shown at F, in which are arranged on each side two vertical and movable bars h l, (see figs. 2 and 3,) which are so arranged as to be capable of a compound vibratory and sliding motion, being hung on pins S S, which pass through slots 1 2 in the said bars h l. To one of these bars l is pivoted at n, (see fig. 3,) a pawl, P, which is formed at one end to catch under a shoulder at o, (see fig. 3,) in the upper part of bar h. The said bars h l are formed with shoulders or projections at v w, on which bear the opposite ends of a spring, m, which passes under a cross-bar or pin i, and which throws down the bars h l in the manner and for the purpose to be presently explained. U is a sliding cam-bar which raises the bars h l, and t is a catch or lock to hold said cam-bar in place.

The operation of the several parts together may be thus explained: The parts being adjusted and locked in the position seen at figs. 1 and 3, the ordinary hook d is placed on the pawl P, as seen at fig. 1. As soon as the boat is thus held and suspended on the hooks, the catch t being raised out of the notch in cam-bar U, the latter is slid out, as seen at fig. 2, when the pawl P and bars h l will still retain their same relative positions in consequence of the weight of the boat being suspended from the pawl P, and the boat may be lowered with perfect safety, but just as soon as the boat A rests in the water, as seen at fig. 2, so that the pawl P is relieved of its weight, then the spring m immediately forces downward the bars h l, which spread apart or diverge from each other at their upper ends, as seen at fig. 2, so as to release the end of pawl P from the bar h, and allow the hook d to slide off of said pawl and the boat to go free. When it is desired to lift the boat, the lock mechanism should be re-adjusted to hold the hook d. By the arrangement of the pins S S, and slots 1 and 2, and spring m, the bars h l can be moved downward and upward in such a direction as to spread open their upper ends and release the pawl P, as shown and described. The said bars are forced up and together by means of the inclines or cam surfaces of the sliding-bar U, (see fig. 3.) It will be seen that with the automatic device described the boat A can be safely lowered, and that the moment the boat rests fairly on the water that moment she is completely released by the automatic operation of the lock, as already explained. And it will be understood that in the use of my invention, if one end of the boat reaches the water first that end only will be let go, and the other will be let go free as soon as it rests on the water sufficiently to take the weight off of the rope at that end.

At fig. 4 I have shown a modification of the apparatus, in which, in lieu of two bars, I have only one bar, h, and have the pawl P pivoted at n² in the stock F of the lock. In this modification the spring m is attached

at one end to the main stock of the lock, and at its other end presses on the shoulder r . This form of lock requires of course only one incline on the bar U ; it is simpler, and may be formed to work quite as well as the other form, shown in figs. 1, 2, and 3. It will be understood that the detail form and arrangement of the parts may be modified in a great variety of ways without departing from the gist of my invention, which is in the idea of the automatically working pawl or catch-bar, or its equivalent, so combined with a movable bar h , or its equivalent, that the former will serve to hold fast to the lowering rope's hook until the boat rests on the water, and will then become immediately disengaged at its vibrating or loose end substantially as already explained.

What I claim as new, and desire to secure by Letters Patent, is—

The combination of the catch-pawl P , locking-bar h , and spring m , with the lock-frame, the whole arranged to operate as described for the purpose set forth.

I also claim an automatic boat-eye or lock, so constructed as to unlock when the weight of the boat rests fairly on the water, substantially as hereinbefore described.

In testimony whereof I have hereunto set my hand and seal this 6th day of May, 1867.

WM. H. HOUSTON. [L. S.]
